UNITED STATES PATENT OFFICE

OLAF A. KINDOM, OF MINNEAPOLIS, MINNESOTA

DESIGN FOR A WHISTLE

Application filed July 13, 1932. Serial No. 44,316. Term of patent 14 years.

To all whom it may concern:

Be it known that I, OLAF A. KINDOM, a citizen of the United States, residing at Minneapolis, in the county of Hennepin and State of Minnesota, have invented a new, original, and ornamental Design for Whistles, of which the following is a specification, reference being had to the accompanying drawing, forming a part thereof, wherein—

Fig. 1 is a view in front elevation of a whistle showing my new design;

Fig. 2 is a view in rear elevation;
Fig. 3 is a view in side elevation looking towards the handle side; and
Fig. 4 is a plan view.

I claim:—
The ornamental design for a whistle substantially as shown.

OLAF A. KINDOM.
